US00D761344S

(12) **United States Design Patent**
Chen

(10) **Patent No.:** **US D761,344 S**
(45) **Date of Patent:** **** Jul. 12, 2016**

(54) **GOGGLES FRAME**

(71) Applicant: **Bor Jye Enterprise Co., Ltd.**, Tainan (TW)

(72) Inventor: **Chun-Nan Chen**, Tainan (TW)

(73) Assignee: **Bor Jye Enterprise Co., Ltd.**, Tainan (TW)

(**) Term: **15 Years**

(21) Appl. No.: **29/526,737**

(22) Filed: **May 13, 2015**

(51) LOC (10) Cl. **16-06**

(52) U.S. Cl.

USPC **D16/312**

(57) **CLAIM**

The ornamental design for a goggles frame, as shown and described.

DESCRIPTION

FIG. 1 is a perspective view of a goggles frame showing my new design;

FIG. 2 is a front side elevational view thereof;

FIG. 3 is a rear side elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines are shown for purposes of illustrating parts that form no part of the claimed design.

1 Claim, 4 Drawing Sheets
